UNITED STATES PATENT OFFICE.

JACKSON W. BROWN, OF DE QUINCY, LOUISIANA, ASSIGNOR OF FORTY-FIVE PER CENT
TO FARRIS E. FARRIS, OF DE QUINCY, LOUISIANA.

RAILWAY CROSSING.

Application filed November 4, 1926. Serial No. 146,256.

This invention relates to new and useful improvements in railway crossings and has for its primary object the provision of a novel and improved coupling for connecting the meeting ends of four railway rails.

Another object of the present invention is to provide an improved coupling of the above class which is characterized by its simplicity and economical construction and which is yet exceedingly strong and durable and practical and efficient in use.

Another object of the present invention is to provide an improved coupling of the above class formed from a single casting 10 provided with recesses for receiving the meeting ends of the four railway rails.

Another object of the present invention is to provide an improved coupling of the above class having associated therewith novel 20 and improved rails of great strength and durability.

A further object of the present invention is the provision of novel rails so constructed that the meeting ends thereof will snugly 25 engage one another whereby to provide a smooth and efficient railway crossing.

Numerous other objects and advantages of the present invention will become more readily apparent during the course of the 30 following description when taken in connection with the accompanying drawings.

In the drawings forming a part of this application and wherein like characters of reference denote corresponding parts 35 throughout the several views:

Figure 1 is top plan view of the crossing constructed in accordance with the present invention.

Figure 4 is a vertical sectional view taken 40 on the line 2—2 of Figure 1.

Figure 3 is a horizontal sectional view taken on the line 3—3 of Figure 2.

Figure 4 is a vertical sectional view taken 45 on the line 4—4 of Figure 1.

Figure 5 is a detail sectional view showing the meeting ends of two alined rails.

Figure 6 is a perspective view of one end 50 of one of the rail sections.

Figure 7 is a perspective view of one end 55 of one of the base sections.

Referring now more in detail to the accompanying drawings, the letters A, B, C and D generally indicate four railway rail couplings provided by the present invention

and which, when used in the manner shown 55 in Figure 1 form a complete railway crossing. Each of the said couplings is adapted for connecting the meeting ends of the four rails 10, 11, 12 and 13 together.

Each of the couplings A, B, C and D is 60 formed from a single casting of the desired metal and embodies the alined seats 14 and 15 and the alined seats 16 and 17 which are disposed at right angles to the first mentioned seats.

Each of the said seats 14, 15, 16 and 17 is provided with a vertical recess 18 the walls of which are defined by spaced flanges 19 and 20, the inner ends of the said recesses 65 communicating with one another at the center of the coupling. The recesses 18 communicate at their lower ends with transversely enlarged recesses 21 which are adapted to receive the bases of said rails.

Each of the said rails comprises a base 75 section 22 shown in Figure 7 and a rail section 23 shown in Figure 6. The base section 22 comprises a flat base portion 24 and an upstanding longitudinally extending flange 25, said flange being slightly off-set from the 80 longitudinal center of said base portion. The base portions 24 of the base sections are adapted to be received within the transverse recesses 21 while the flanges 25 are adapted to be received within the recesses 18. As 85 shown, the ends of the base portions 24 of the rails 10, 11 and 12 are beveled to provide the converging edge faces 26 and 27 connected by a straight edge face 28 while the ends of the rail 13 are provided with the 90 beveled converging edge faces 30 and 31 and a tongue 29. The beveled edges 30 and 31 of the rail 13 engage the adjacent beveled edges of the rails 10 and 12 while the tongue 29 engages the flat edge faces 28 of the rails 95 10, 11 and 12 as clearly shown in Figure 3. It will of course be appreciated that either one of the rails 10, 11, 12 or 13 may be provided with the tongue 29 and this tongue is provided so that the meeting ends of the 100 rails will snugly engage one another whereby to provide a smooth crossing.

The rail section 23 embodies a rail engaging portion 32 and a depending web 33 which is received within the recess 18 in 105 the coupling and which is adapted to rest at its lower edge upon the base portion 24 of the rail section and facially abut the

flange 25. Thus, it will be seen that there has been provided a rail of double strength and one which can be subjected to unusual hard usage without damaging the same.

5 The flanges 25 and webs 33 are provided with alined openings 34 and 35 through which are adapted to be inserted suitable fastening bolts 36 which pass transversely through the flanges 19 and 20 of the coupling. Each of the said rails is also provided with a notch 37 to compensate for the customary flanges formed on car wheels.

With the above construction, it will be evident that there has been provided a novel and simplified coupling for connecting the meeting ends of four railway rails and that both the couplings and rails employed are of a novel and efficient yet simple and durable construction.

20 Changes in the details of construction may be resorted to without departing from or sacrificing the spirit of the invention so long as such changes fall within the scope of the appended claims.

25 What is claimed is:

1. The combination with a railway crossing coupling provided with two pairs of alined recesses disposed at an angle to one another, of a plurality of rails received within said recesses, each rail consisting of a base section and a rail section, the meeting ends of said rails being beveled and snugly engaging one another.

2. The combination with a railway crossing coupling provided with two pairs of alined recesses disposed at an angle to one another, of a plurality of rails received within said recesses, each rail including a base section consisting of a base portion and an upstanding flange and a rail section consisting of a rail engaging portion and a depending web adapted to rest upon the said base portion and abut the upstanding flange, the meeting ends of said rails being beveled and snugly engaging one another.

3. The combination with a railway crossing coupling provided with a pair of alined recesses for receiving the meeting ends of two rails and a second pair of alined recesses disposed at an angle to the first named recesses for receiving the meeting ends of two other rails, of a plurality of rails received within said recesses, each rail including a base section consisting of a base portion and an upstanding flange and a rail section consisting of a rail engaging portion and a depending web adapted to rest upon said base portion, the meeting ends of the

said base portions being beveled and snugly engaging one another.

4. The combination with a railway crossing coupling provided with two pairs of alined recesses disposed at an angle to one another, of a plurality of rails received within said recesses, the meeting ends of said rails being beveled and snugly engaging one another.

5. The combination with a railway crossing coupling provided with two pairs of alined recesses disposed at an angle to each other, the recesses being widened at their bottoms and the side walls of the recesses being defined by upstanding flanges, of a plurality of rails received within the recesses, each rail including a base section consisting of a base portion and an upstanding flange, the base portion being seated within the enlarged bottom portion of the respective recess and the upstanding flange being received within the recess and abutting against one wall thereof, each rail further including a rail section consisting of a head portion and a depending web, the depending web of the said rail section abutting against and received between the other wall of the respective recess and the upstanding flange of the respective base section with its lower edge resting upon the base portion of the base section, the meeting ends of the said rails abutting, and securing means passed through the said walls of the recesses of the crossing coupling and through the upstanding flanges and depending webs of the rail sections received therebetween.

6. The combination with a railway crossing coupling provided with two pairs of alined recesses disposed at an angle to each other, of a plurality of rails received within said recesses, each rail including a base section consisting of a base portion and an upstanding flange, the base portion of one rail having angular end portions and a tongue extending beyond the same, the base section of the rail alined therewith having angular end portions and an intervening straight portion the latter abutting the end of the tongue, the base sections of the other rails having angular portions abutting the angular portions of the base sections of the first mentioned rails and having straight intervening portions abutting the opposite sides of the tongue of the first mentioned rail.

In testimony whereof he does affix his signature.

JACKSON W. BROWN.
